(57) **CLAIM**

The ornamental design for a beverage cartridge rack, as shown and described.

DESCRIPTION

FIG. 1 is a top, front perspective view of a first embodiment of a beverage cartridge rack showing my new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is another top, front perspective view thereof;

FIG. 8 is a top, rear perspective view thereof;

FIG. 9 is another top, rear perspective view thereof;

FIG. 10 is another right side elevational view thereof;

FIG. 11 is a top, front perspective view of a second embodiment of a beverage cartridge rack showing my new design;

FIG. 12 is a front elevational view thereof;

FIG. 13 is a top plan view thereof;

FIG. 14 is a bottom plan view thereof;

FIG. 15 is a right side elevational view thereof;

FIG. 16 is a left side elevational view thereof;

FIG. 17 is a top, front perspective view of a third embodiment of a beverage cartridge rack showing my new design;

FIG. 18 is a front elevational view thereof;

FIG. 19 is a top plan view thereof;

FIG. 20 is a bottom plan view thereof;

FIG. 21 is a right side elevational view thereof;

FIG. 22 is a left side elevational view thereof;

FIG. 23 is a top, front perspective view of a fourth embodiment of a beverage cartridge rack showing my new design;

FIG. 24 is a front elevational view thereof;

FIG. 25 is a top plan view thereof;

FIG. 26 is a bottom plan view thereof;

FIG. 27 is a right side elevational view thereof; and,

FIG. 28 is a left side elevational view thereof.

The broken lines in FIGS. 1-28 represent portions of the beverage cartridge rack that form no part of the claimed design.

1 Claim, 17 Drawing Sheets
